JAKOB KOPELIOWITSCH, OF BADEN, SWITZERLAND, ASSIGNOR TO AKTIENGESELLSCHAFT BROWN BOVERI & CIE, OF BADEN, SWITZERLAND, A JOINT-STOCK COMPANY OF SWITZERLAND

SWITCH

Application filed January 6, 1931, Serial No. 506,956, and in Germany January 6, 1931.

This invention relates to improvements in electric current circuit breakers and particularly to circuit breakers in which the arc is quenched in a fluid normally retained in a chamber under pressure.

The usual circuit breaker for high voltages and/or high current is provided with a so-called explosion chamber filled with an insulating material in which the contacts are immersed and which aids in quenching the arc struck when the contacts are separated. The fluid, which is usually oil, may be maintained under pressure from an external source or pressure may be produced by the action of the arc during the circuit interrupting operation. Such constructions are however not sufficiently effective for the voltages and currents interrupted in present day practice.

It is, therefore, among the objects of the present invention to provide a circuit breaker in which the contacts are separated, and the arc therefore struck, in air and at least one of the contacts is drawn into a fluid which aids in quenching the arc.

Another object of the invention is to provide a circuit breaker in which the contacts are separated in air and the arc is drawn into a chamber filled with a quenching fluid retained under pressure from an external source of fluid supply.

Another object of the invention is to provide a circuit breaker in which the contacts are separated in air and the arc is drawn into a chamber filled with a quenching fluid retained under pressure from an external source of fluid supply which is cut off when the contacts are separated.

Objects and advantages, other than those above set forth, will be apparent from the following description when read in connection with the accompanying drawing which somewhat schematically illustrates one embodiment of the present invention.

Referring more particularly to the drawing illustrating schematically one embodiment of the invention, the reference numeral 1 designates a contact member which is preferably adapted to be retained in a fixed position by suitable means well-known to the art such, for purpose of illustration, as the in-

sulating member 20. A contact member 2 extends upward through a pressure-tight quenching chamber 3 and is arranged to be drawn downwardly thereinto by any suitable operating means such, for example, as the lever 21, toggle 22 and handle lever 23.

A quenching chamber 3 is provided, at its upper end, with a closure 4 of suitable insulating material having an aperture therethrough defined by an upwardly extending wall which forms a nozzle 6 through which the movable contact 2 extends into engagement with the fixed contact 1. The top closure member 4 of the chamber 3 is retained in position thereon by means of a suitable cap 7 detachably secured, as by screw threads, on the chamber. The bottom of chamber 3 is provided with a sealing gland including an insulating member 8 through which the contact 2 may move and which prevents the loss of oil, or other suitable liquid, under pressure therefrom.

The chamber 3 is supplied with oil or other suitable liquid under pressure from a suitable source of supply such, for example, as the reservoir 24 by means of conduit 25 connected with the chamber at 9 which pressure is controlled by a valve 11 operated by a gear sector 12 meshing with a rack 13 formed on the movable contact 2. As long as contact 2 is in the position shown, valve 11 is open but when the contacts are separated by moving contact 2 downwardly, the downward movement of the rack formed thereon closes the pipe line 9 supplying the fluid pressure. The oil under pressure in chamber 3 is prevented from escaping through nozzle 6 as long as the contacts are in the position shown i. e. closed, by means of a valve member 16, retained under the pressure of a spring 17, between collars 18 and 19 on the movable contact 2 and seated against the closure member 4.

When the switch is closed and both contacts are therefore in the position shown, valve 11 is opened and valve 16 is held in such a position by spring 17 as to close the nozzle 6. The liquid under pressure may thus fill chamber 3 completely. As soon as the contacts are separated, an arc is struck in

air and is drawn downward, by movement of contact 2, into chamber 3. Shortly after the beginning of the downward movement of contact 2 the collar 18 engages and moves to its open position, valve member 16 followed by the movement of valve member 16 to closed position. The supply of fluid under pressure is thus shut off but the pressure in chamber 3, is increased by the action of the arc in the 10 fluid and a stream of quenching fluid under pressure flows through nozzle 6 about the arc drawn therethrough which is quickly quenched thereby. When the switch is reclosed, contact 2 reopens valve 11 and recloses 15 valve 16 thereby permitting re-establishment of the fluid pressure in chamber 3 and the switch is then ready for a second circuit breaking operation.

It will be understood that the arc attaching portions of the contacts are replaceable and that both contacts may be provided with quenching chambers as shown for contact 2 in which case both contacts are movable in opposite directions. An interlock may also 20 be provided for the movable contact of such nature as to prevent opening of the switch unless the fluid pressure in the quenching chamber is at a pre-determined value.

Although but one embodiment of the present 30 invention has been illustrated and described, it will be apparent to those skilled in the art that various changes and modifications may be made therein without departing from the spirit of the invention or 35 from the scope of the appended claims.

The invention claim is:

1. In an electric current circuit breaker, a 40 pair of contacts, a chamber retaining a fluid under pressure, one of said contacts being movable into said chamber, a pipe line supplying fluid under pressure to said chamber, and valves to control the supply of fluid to said chamber and to control the escape of fluid therefrom.

45 2. In an electric current circuit breaker, a pair of contacts, a chamber retaining a fluid under pressure, one of said contacts being movable into said chamber, a pipe line supplying fluid under pressure to said chamber, and valves operated by said movable contact to control the supply of fluid to said chamber and to control the escape of fluid therefrom.

55 3. In an electric current circuit breaker, a pair of contacts, a chamber retaining a fluid under pressure, one of said contacts being movable into said chamber, a pipe line supplying fluid under pressure to said chamber, a valve operated by said movable contact to control the supply of fluid to said chamber, and a valve carried by said movable contact to control the escape of fluid from said chamber.

60 4. In an electric current circuit breaker, a pair of contacts, a chamber retaining a

fluid under pressure, one of said contacts being movable into said chamber through a nozzle formed thereon, a pipe line supplying fluid under pressure to said chamber, a valve operated by said movable contact to control the supply of fluid to said chamber, and a valve carried by said movable contact to control the escape of fluid from said chamber, said last-mentioned valve opening only after separation of said contact. 75

5. In an electric current circuit breaker, a chamber retaining a fluid therein and having an aperture therethrough forming a nozzle for the flow of said fluid therefrom, a pair of cooperating circuit controlling contacts, 80 one of said contacts being movable through said aperture into said chamber, a valve operable to control the flow of fluid into said chamber, and a valve operable to control the flow of said fluid from said chamber by 85 way of said aperture upon said movement of the said one of said contacts into the chamber.

6. In an electric current circuit breaker, a chamber retaining a fluid therein and having an aperture therethrough forming a nozzle for the flow of said fluid therefrom, a pair of cooperating circuit controlling contacts, one of said contacts being movable through and operative into and out of said chamber, a pipe line for supplying said fluid to said chamber, a valve operable to control the said supply of said fluid to said chamber, and a valve operable to control the flow of fluid from said chamber by way of said 90 aperture, the said movement of the said one of said contacts into said chamber being operative to first actuate the last said valve to permit the said flow of fluid from the chamber and to thereafter actuate the first said 95 valve to prevent the said flow of fluid into the chamber. 105

In testimony whereof I have hereunto subscribed my name this 23 day of December A. D. 1930.

110 JAKOB KOPELIOWITSCH.
